(57) **CLAIM**

I claim the ornamental design for a tuner for musical instrument, as shown and described.

DESCRIPTION

FIG. 1 is left elevation view of a head portion of the tuner for musical instrument;

FIG. 2 is a front elevation view thereof;

FIG. 3 is a right elevation view thereof;

FIG. 4 is a rear elevation view thereof;

FIG. 5 is a top plan view thereof; and

FIG. 6 is a bottom plan view thereof.

FIG. 7 is a left elevation view of the tuner for musical instrument, showing my new design;

FIG. 8 is a front elevation view thereof;

FIG. 9 is a left elevation view thereof;

FIG. 10 is a rear elevation view thereof;

FIG. 11 is a bottom plan view thereof; and,

FIG. 12 is a top plan view thereof.
